UNITED STATES PATENT OFFICE.

ANDREAS MALSCH, OF MUNICH, GERMANY.

GRINDING-MILL.

SPECIFICATION forming part of Letters Patent No. 445,227, dated January 27, 1891.

Application filed September 27, 1888. Serial No. 286,512. (No model.)

To all whom it may concern:

Be it known that I, ANDREAS MALSCH, of Munich, Germany, have invented a new and Improved Grinding-Mill, of which the following is a specification.

This invention relates to various improvements in grinding-mills; and it consists in the features of improvement more fully pointed out in the claims.

10 In the accompanying drawings, Figure I is an elevation, partly in section, of my improved grinding-mill. Fig. II is an enlarged elevation, partly in section, of the upper part thereof. Fig. III is a similar elevation of the 15 lower part thereof, and Fig. IV a top view of cylinder *y*.

The letter *a* represents the bed-stone, that may be revolved by gear-wheel *l'* on shaft *l*, said gear-wheel engaging the corrugated 20 flange *l'* on stone *a*. The bed-stone *a* has a central shaft *a'*, that is received by the hub *a*² of the lower cylinder *y*, hereinafter described, and which serves to keep the bed-stone in its proper central position. The 25 stone *a* revolves upon an upper cylinder *x*, which in turn rests upon a lower cylinder *y*, the cylinders *x* *y* constituting the foundation. The contact-edges of the parts *x* *y* are made in the shape of three more or less inclined 30 steps, so that the cylinder *x* when turned toward the left will be forced up the inclined surface of the cylinder *y*, and will thus be raised, carrying stone *a* up with it.

The drawings represent the cylinder *x* in 35 its lowest position. In order to revolve it and maintain it at any desired elevation, an inclined rack *x'* runs along the periphery of cylinder *x*. This rack is engaged by a worm *y'*, fast on shaft *y*⁵, that may be revolved by 40 crank *y*³. At its bottom the cylinder *y* is provided with a flange *y'*, to which the leveling-screws *y*² are secured. Thus the bed-stone may be leveled and may also be raised and lowered. The shaft *b*, that rotates the runners, is placed eccentrically to the shaft *a'* of the bed-stone. Thus the runners traverse the entire surface of the bed-stone. The shaft *b* is surrounded by a cylindrical sleeve *L*, fast on cross-beam *L'*. To the lower end of this

sleeve there is rigidly secured the bevel-wheel *Z*. The shaft *b* projects beneath this wheel and carries by hub *d'* a drum *d*, that revolves with the shaft.

e e are the inclined spindles of the runners C. These spindles project into drum *d* and carry at their inner ends the bevel-wheels *Z'*, engaging the bevel-wheel *Z*. The rotation of shaft *b* will cause the drum *d* to revolve, and the latter will cause the runners to travel over the bed-stone. The bevel-gear *Z* *Z'* insures a uniform rotation of the runners. The runners C may be adjusted higher up or lower down upon their spindles *e* by means of nuts *k* *k'*.

In order to lubricate the spindles *e* and to prevent the lubricant from dropping upon the bed-stone, I employ the following construction: Within the drum *d* each spindle *e* is surrounded by a perforated disk *S*, carrying the lubricator-cup *S'*. At its outer end—that is, directly back of runner C—the spindle *e* terminates in a chamber *e*², placed in front of a stuffing-box *e'*. On the rotation of the spindles the lubricant introduced at *S'* will be thrown outward by centrifugal force. Thus the lubricant will, through stuffing-box *e'*, enter chamber *e*², which collects it and prevents it from dripping down. The chamber *e*² can be cleaned out every few days.

This improved mill will cause a uniform wearing of the stones and will bring all the matter to be ground between the stones.

What I claim is—

1. The combination of bed-stone *a*, having central shaft *a'* and flange *l'*, with shaft *l* and gear-wheel *l'*, that engages said flange, a pair of cylinders *x* *y*, having inclined contact-edges, a rack *x'* on periphery of cylinder *x*, a crank-shaft *y*⁵, having worm *y'*, engaging said rack, and with a hub *a*² in cylinder *y* for receiving shaft *a'*, substantially as specified.

2. The combination of bed-stone *a* with cross-beam *L'*, sleeve *L*, secured thereto and placed eccentrically to the bed-stone, and with bevel-wheel *Z*, secured to the sleeve, a shaft *b*, passing through the sleeve, a drum *d*, secured to the shaft, and runners C, having spindles *e*, that project into the drum and are inter-

geared with wheel Z, substantially as specified.

3. The combination of suspended sleeve L, carrying bevel-wheel Z, with inclosed shaft 5 b, carrying drum d, and with runners C, having spindles e, that pass through the drum and are intergeared with wheel Z, and with

the perforated disk S, lubricator S', nuts k k', and chamber e² on spindles e, substantially as specified.

ANDREAS MALSCH.
